UNITED STATES PATENT OFFICE.

OTTO SINDL, OF BRESLAU-CARLOWITZ, GERMANY, ASSIGNOR TO THE FIRM THE NUERA ART-SILK COMPANY LIMITED, OF SUTTON OAK, NEAR ST. HELENS, LANCASHIRE, ENGLAND.

DEVICE FOR STRAINING SKEINS OF ARTIFICIAL SILK.

Application filed January 30, 1928, Serial No. 250,593, and in Germany February 5, 1927.

It is known that in the manufacture of artificial silk of viscose the finished strands of the raw silk, after having been washed for the first time, are subjected to a drying process and, simultaneously therewith, to tension, the skeins being supported on bars while the drying proceeds and these bars being supported singly on travelling frames, or straining trucks respectively. Placing the bars upon said frames or trucks is a work which easily entails mechanical damage to the threads or skeins of the artificial silk, and besides, the complete charging of a frame which is to receive as large a number of skeins as possible requires a certain time so that always a comparatively large number must be available in order to prevent interruptions of the regular work.

The present invention relates to a straining truck in which the part carrying the bars with the skeins is formed by a separate frame whereby it is rendered possible to charge any desired number of such frames outside the straining truck and to interchange quickly a frame with skeins to be treated for a frame with treated skeins. Another advantage resides therein that the separate interchangeable frames can be used also in the preceding working phases, as well as in the subsequent ones, so that the bars with the skeins need not be removed from one place and conveyed to another place but remain located upon the respective frame or frames, whereby loss of time, as well as damage to the ware, is completely prevented. The interchangeable frames need not be designed for particularly great stress as they can be supported upon the trucks on rails extending along the entire length of the trucks so that the frames are not in the least subjected to bending stress.

The invention is illustrated diagrammatically and by way of example on the accompanying drawing on which Figure 1 is a side-view of an interchangeable straining frame designed according to this invention, and Figure 2 is a frontal view of the same.

On the drawing, 1 denotes the interchangeable frame proper, 2 the bars carrying the skeins of the artificial silk, 3 these skeins, 4 weighting bars by which the skeins are kept straight in vertical direction, and 5 denotes rails supporting the frame 2 whereby these latter are securely prevented from bending through. There are upper rails 5 and lower

rails 5^a and between the rails 5 and 5^a is a spreading mechanism by which the lower bars can be moved downwardly so as to subject the skein 3 to tensile strain. Said mechanism comprises U-shaped double eyes 6 secured to the rails 5 and 5^a, the upper double-eyes being directed downwardly, the lower ones upwardly; links 7 hinged to the upper and the lower eyes 6; double-eyes 8 connected in pairs by threaded sleeves 9; and a spindle 10 which is threaded where there are the sleeves 9. The threaded portions of the spindle 10 are alternately lefthand-threaded and righthand-threaded so that the sleeves 9 are moved either towards, or away from, each other, according to the direction of rotation of the spindle. When they are moved towards each other the skeins are strained, as will be clear without a further detailed explanation.

In order to prevent the frame 1 from being affected by chemical influences it is preferably made of a suitable substance or composition or covered with a layer of such a one, for instance with a hardened artificial resin or with a mixture of such a one and a mixture of fibres.

I claim:

1. A device for straining skeins of artificial silk, comprising, in combination with the bars provided for receiving the threads or skeins, an interchangeable frame adapted to receive and support said bars and to be attached to, and detached from, a suitably designed travelling truck adapted to receive and support said interchangeable frame.

2. A device for straining skeins of artificial silk, comprising, in combination with the bars provided for receiving the threads or skeins, an interchangeable frame adapted to receive and support said bars and to be attached to, and detached from, a suitably designed travelling truck adapted to receive and support said interchangeable frame, and supporting rails arranged below the longitudinal members of the said frame and extending along the entire length of them, substantially and for the purpose set forth.

3. A device for straining skeins of artificial silk, comprising, in combination with the bars provided for receiving the threads or skeins, an interchangeable frame adapted to receive and support said bars and to be attached to, and detached from, a suitably de-

signed travelling truck adapted to receive and support said interchangeable frame, this latter consisting of a material which is practically not affected by chemical influences.

5. 4. A device for straining skeins of artificial silk, comprising, in combination with the bars provided for receiving the threads or skeins, an interchangeable frame adapted to receive and support said bars and to be attached to, and detached from, a suitably designed travelling truck adapted to receive and support said interchangeable frame, and a covering for this latter consisting of a material which is practically not affected by chemical influences.

10. 5. A device for straining skeins of artificial silk, comprising, in combination with the bars provided for receiving the threads or skeins, an interchangeable frame adapted to

receive and support said bars and to be attached to, and detached from, a suitably designed travelling truck adapted to receive and support said interchangeable frame, this latter consisting of hardened artificial resins, for the purpose set forth.

25. 6. A device for straining skeins of artificial silk, comprising, in combination with the bars provided for receiving the threads or skeins, an interchangeable frame adapted to receive and support said bars and to be attached to, and detached from, a suitably designed travelling truck adapted to receive and support said interchangeable frame, this latter being covered with a mixture of artificial resins and mixtures of fibres, for the purpose set forth.

In testimony whereof I affix my signature.
OTTO SINDL.
